United States Patent Office

Des. 227,505
Patented June 26, 1973

227,505

SLIDE PROJECTOR

Gerald J. Frey, Suite 202, 3887 State St.,
Santa Barbara, Calif. 93105

Filed July 17, 1972, Ser. No. 272,453

Term of patent 14 years

Int. Cl. D16—02

U.S. Cl. D61—1 J

Fig. 1

Fig. 2

Fig. 3

Fig. 4

Fig. 5

Fig. 6

FIG. 1 is a front perspective view of a slide projector showing my new design:

FIG. 2 is a right side elevational view thereof;

FIG. 3 is a top plan view thereof;

FIG. 4 is a bottom plan view thereof;

FIG. 5 is a rear elevational view thereof;

FIG. 6 is a perspective view thereof in a carrying position with the handle raised.

I claim:

The design for a slide projector, substantially as shown and described.
